United States Patent Office

Des. 180,140
Patented Apr. 23, 1957

180,140

SETTEE OR SIMILAR ARTICLE

Morris Futorian, Glencoe, Ill.

Application March 21, 1955, Serial No. 35,125

Term of patent 7 years

(Cl. D15—11)

The single drawing figure is a perspective view of a settee or similar article showing my new design.

The back of the settee or similar article is substantially plain.

The broken away portion shown in the drawing is to indicate indefinite length.

I claim:

The ornamental design for a settee or similar article as shown and described.
